FEMALE FASTENER FOR RETAINING LICENSE PLATES, AND LIKE PURPOSES

Yale Ginsberg, Bloomfield Hills, Mich., assignor to Car-Pak Manufacturing Co., Inc., Troy, Mich., a corporation of Michigan

Filed Apr. 21, 1969, Ser. No. 16,820

Term of patent 14 years

Int. Cl. D8—04
U.S. Cl. D8—273

FIG. 1

FIG. 2

FIG. 6

FIG. 4

FIG. 3

FIG. 5

FIG. 7

FIG. 1 is a perspective view from the bottom and a first side of a female fastener for retaining license plates, and like purposes embodying my new design;

FIG. 2 is a perspective view from the bottom and a second side;

FIG. 3 is a top view;

FIG. 4 is a view from the first side;

FIG. 5 is a view from the second side;

FIG. 6 is a view from a third side normal to the first and second side;

FIG. 7 is a view from a fourth side opposite to the third side.

I claim:

The ornamental design for a female fastener for retaining license plates, and like purposes, as shown.
